CASING FOR TEACHING DEVICE

Jack L. Lamberson, Miami, Fla. (3825 S. Monaco Parkway, No. 152, Denver, Colo. 80237)

Filed Aug. 13, 1969, Ser. No. 18,657

Term of patent 14 years

Int. Cl. D19—08

U.S. Cl. D25—1

FIG. 1

FIG. 2

FIG. 3

FIG. 4

FIG. 5

FIG. 1 is a top plan view of a casing for teaching device showing my new design.

FIG. 2 is a side elevational view thereof.

FIG. 3 is a front elevational view thereof.

FIG. 4 is a bottom plan view thereof.

FIG. 5 is a rear elevation thereof.

The side not shown is the same as shown in FIG. 2.

I claim:

The ornamental design for a casing for teaching device, as shown and described.
